UNITED STATES PATENT OFFICE

2,003,438

TOOL FOR MAKING CARTRIDGE SHELLS

Léon Auguste Guignet, La Varenne Ste. Hilaire, France, assignor to The Compagnie Royale Asturienne des Mines, Paris, France, a corporation of Belgium

Original application March 1, 1933, Serial No. 659,115, now Patent No. 1,974,270, dated September 18, 1934. Divided and this application September 9, 1933, Serial No. 688,760. In Germany January 17, 1933

3 Claims. (Cl. 153—48)

This invention relates to a tool for the manufacture of metal cartridge shells, this application being a division of my Patent No. 1,974,270, filed March 1, 1933 in which I have disclosed and 5 claimed a metal cartridge shell having a double fold in the shell between the base and the tubular part of the shell, the crowns of said fold having a relatively large radius of curvature so as to readily withstand the internal gas pressure upon 10 firing.

The present invention has for its object a tool for manufacturing shells of this character.

Another object is to provide a tool by which 15 said shells can be manufactured expeditiously and with a minimum number of operations.

Other objects and advantages will hereinafter appear.

The accompanying drawings illustrate, by way 20 of example, a constructional embodiment of the new tool and its operation.

In the drawings

Figure 1 is a longitudinal cross section of the lower part of a completed shell having a relatively thick bottom portion and a relatively thin 25 side portion of substantially uniform cross section.

Fig. 2 is a longitudinal section of an intermediate form of a shell during its manufacture and prior to its insertion in the present tool for the 30 finishing operation.

Fig. 3 is a longitudinal section of the tool while the shell blank illustrated in Fig. 2 is being inserted.

Fig. 4 is a longitudinal section of the tool at 35 the end of the forming operation of the completed shell.

Fig. 5 is a detail cross section of parts 6, 6 on line 5—5 in Fig. 3, looking in the direction of the arrows.

40 Referring to the drawings, the same illustrate a tool for the final conversion of a unitary shell blank as illustrated in Fig. 2 into a completed cartridge shell as illustrated in Fig. 1, said shell having a tubular side wall 1 of either constant or of tapered cross section which is merged into a base 2 of preferably greater thickness than the wall 1 through a double fold consisting of an outer convolution 4 and an inner convolution 5, the cross section of the connection between the convolution 4 and a bottom rim 3 being preferably 45 tapered and the crowns of both convolutions of the fold having a substantial radius in cross section so as not to cause overstraining of the material during formation and when subjected to 50 internal pressure upon firing.

The tool consists of two portions, the upper portion A being preferably arranged for mounting on the ram of a drawing or punching press, while the lower portion B is preferably arranged for fastening to the stationary platen of the press.

5 The portion A is provided with a longitudinal conical central bore adapted to receive a frustated conical liner 6 which is radially divided into two halves as indicated by Fig. 5. The liner is provided with a central bore 19 approximately corresponding to the outside diameter of the shell blank. Arranged inside of said bore is a mandril 7, having a collar 20, said mandril being fixedly attached to the body of the part A. The axial length of the liner 6 is slightly less than the corresponding bore in the body A so as to provide a space 17 between the upper end of the liner and the collar 20, said collar being recessed in the body A so as to form an abutment for the mandril 7 and also for the liner 6 so as to limit the lateral movement of the latter with respect 10 to the body A.

15 The lower end of the mandril 7 is provided with a bevel 11 of such shape as to aid in the formation of the inner fold or convolution 5 of the shell. The mandril 7 has a central bore in which 20 is slidably mounted an ejector pin 9, the upper part of said ejector pin being provided with a collar which limits its downward movement. The 25 ejector pin is urged downwardly by a spring 8. The diameter of the mandril 7 is such as to correspond to the inside diameter of the shell, thus 30 providing for a space between the mandril and the liner for the introduction of a shell blank as illustrated in Figs. 2 and 3. A recess 10 is 35 provided at the lower end of the bore 19 of the liner 6 of such shape as to facilitate the formation of the outside fold or convolution of the shell. In the downward direction the liner is prevented from sliding out of the body A by means of a collar 40 18a having a bore 18 of suitable diameter.

45 The lower part B of the tool is provided with an annular flange or ring 14 which is slidably guided in said body by means of a number of rods 15. The upward movement of said flange is limited by a number of screws 21. The rods 15 at their lower free end abut against a collar 16 which is urged upwardly by means of a heavy spring 13. In a central bore of the flange 14 is slidably 50 mounted a plunger 12, said plunger being fixedly attached to the body B. The bore 18 of the upper part of the tool is of such diameter as to pass the upper end of the flange 14 and permit it to bear against the liner 6.

55 The shell consists of a tubular part 1 and a base 55

2. The blank is first drawn in the usual manner, the bottom having a constant thickness which may be greater than that of the tubular part and the wall of the tubular part may be slightly tapered or may be straight. It will be understood that the portions shown in Figs. 1 and 2 are somewhat exaggerated. As an example, the thickness of the top end of the tubular part may be .23 mm., while the thickness of the tubular part 5 near the base may be .3 mm., and the constant thickness of the base may also be .3 mm., or may have a thickness of as much as .7 mm., the latter proportion approximately corresponding to the proportion shown in paragraph 1.

10 The tool operates in the following manner: After the shell blank 1 is inserted in the upper part A of the tool as illustrated in Fig. 3, the ram of the press is lowered and the upper part A moved towards the lower part B. The shell is 15 pushed into the recess 19 approximately to the point where its base 2 abuts against the ejector pin 9. Approximately at the same time the flange 14 touches the lower surface of the liner 6 so that upon further downward movement 20 the flange is urged downward against the pressure of the spring 13. As this spring pressure is relatively high, it resists the downward movement of the flange and causes movement of the liner longitudinally in the part A and thus causes 25 the latter to close in radially on the tubular part of the shell 1 so as to press it tightly against the mandril 7 and prevent it from further upward movement. The liner slides in the part A until the air gap 17 has been closed, whereupon its further longitudinal movement is prevented by abutment against the collar 20. Upon further movement of the part A, the spring 13 is compressed 30 by the downward movement of the flange 14 and ultimately the shell blank makes contact with 35 the plunger 12. This plunger thereupon drives the material of the shell upwardly and causes 40 it to fold, said folding being guided by the recesses 10 in the liner 6 and the bevel 11 of the mandril 7. The bore 10 also determines the 45 outside diameter of the shell rim. The relative position of the tools is ultimately as illustrated in Fig. 4 in which the shell has its final shape. Thereafter the ram of the machine is raised and the parts A and B separate again. This movement finally releases the upward pressure on the 50 liner 6 and the latter opens up radially and permits the shell to be ejected from the part A by the action of the spring 8 on the ejector pin 9, the spring having been previously compressed 55 by the upward movement of the base of the shell and of the ejector pin 9 after contact of the base with the plunger 12.

The described apparatus produces a shell from a blank in a single operation instead of a number of complicated and difficult operations required by other known means. It further assures a shell, the material of which has not been subjected to

undue strains which may cause it to yield and crack upon subsequent firing. The tool with obvious modifications may also be used for the manufacture of other types of shells than the one herein illustrated and described and I therefore do not wish to limit the appended claims to a tool for manufacturing the shell illustrated herein.

What I claim as new and desire to secure by Letters Patent is:

1. A tool for the production of a double fold between the bottom and the side of a unitary cartridge shell, comprising an upper part, said upper part comprising a mandril for said shell, having a beveled lower end adapted to produce the inner convolution of said fold upon application of an axial thrust upon said shell, a divided liner shaped and adapted to move radially to grip said shell and having a recess adapted to produce the outer convolution of said fold upon application of said thrust, and a lower part, 20 the latter comprising a fixed plunger, a relatively movable flange surrounding said plunger, and adapted to engage said liner to cause it to move laterally and a biasing spring tending to oppose movement of said flange. 25

2. A tool for the production of a double fold between the bottom and the side of a unitary cartridge shell, comprising an upper part, said upper part comprising a mandril for said shell having a beveled lower end adapted to produce 30 the inner convolution of said fold, a spring biased element concentric with said mandril tending to push said shell out of engagement therewith, a divided liner shaped and adapted to move radially to grip said shell and having a recess 35 adapted to produce the outer convolution of said fold, and a lower part, the latter comprising a fixed plunger, a relatively movable flange surrounding said plunger, and adapted to engage said liner to cause it to move laterally and a 40 biasing spring tending to oppose movement of said flange. 45

3. A tool for the production of a double fold between the bottom and the side of a unitary cartridge shell, comprising an upper part, said 50 upper part comprising a mandril for said shell, having a beveled lower end adapted to produce the inner convolutions of said fold upon application of an axial thrust upon said shell, a spring biased element concentric with said mandril 55 tending to push said shell out of engagement therewith, a divided liner shaped and adapted to move radially to grip said shell and having a recess adapted to produce the outer convolution of said fold, and a lower part, the latter comprising a fixed plunger, a relatively movable flange surrounding said plunger, and adapted to engage said liner to cause it to move laterally and a biasing spring tending to oppose movement of said flange. 60

LÉON AUGUSTE GUINET.
